W. L. JACOBS.

CARPET.

No. 17,488.

Patented July 26, 1887

UNITED STATES PATENT OFFICE.

WINTHROP L. JACOBS, OF EAST ORANGE, NEW JERSEY, ASSIGNOR TO THE
HARTFORD CARPET COMPANY, OF HARTFORD, CONNECTICUT.

DESIGN FOR A CARPET.

SPECIFICATION forming part of **Design No. 17,488**, dated **July 26, 1887**.

Application filed June 15, 1887. Serial No. 241,436. Term of patent 3½ years.

To all whom it may concern:

Be it known that I, WINTHROP L. JACOBS, of East Orange, New Jersey, have invented a new and original Design for Carpets, of which 5 the following is a specification, reference being had to the accompanying photograph, which forms a part of the same.

The invention relates to a design to be worked into or upon surfaces, such as carpets 10 or similar fabrics; and it consists in the novel configuration and grouping of figures herein specifically shown and claimed.

The accompanying photograph is a face view 15 of a carpet showing my new design.

The main feature of my design is the figure

A, which consists of a central stem with branches projecting from both sides, some of these branches supporting at their ends circular forms resembling blossoms or fruit. The figure A is repeated, as shown, upon any suitable ground-work.

What I claim as new, and desire to secure by Letters Patent, is—

The design for carpets, consisting of the design substantially as shown.

W. L. JACOBS.
